UNITED STATES PATENT OFFICE.

WILLIAM T. BATTLE, OF PROVIDENCE, RHODE ISLAND, ASSIGNOR TO GEORGE F. BERKANDER, OF PROVIDENCE, RHODE ISLAND.

BARRETTE.

Application filed March 31, 1925. Serial No. 19,586.

This invention relates to barrettes and has for its particular objects the provision of a device which cannot be entangled in the hair of the wearer and which also can 5 easily be positioned or removed from the head.

I have accomplished these desired results by devising a novel form of spring snap pin with a closed free end and a catch therefor 10 with a wide mouth and sides that slope inwardly a certain distance and the bear outwardly to form a resting place for the pin. This construction furnishes a secure locking while the barrette is being worn and also 15 permits of its being positioned and locked in place, or removed therefrom by the use of the thumb and one finger of one hand of the wearer.

I am familiar with the previous patents 20 on devices of this nature, but am not aware of any constructions which embody the novel features set forth in the following specification and shown in the accompanying drawings in which:—

25 Fig. 1 is a side view of the device.
Fig. 2 is a view of the under side thereof.

Fig. 3 is a sectional view on the line 3—3 of Fig. 1.

As shown, the barrette consists of a body 30 10 which can be made of any desired ornamental type, this being the only portion visible when the device is in use.

On the under side of this body 10, the 35 spring pin 11 is hingedly secured at one end to the ring 12 with its free end 13 shaped for engagement with the catch 14. The spring pin 11 is formed with a closed ring end 15 for engagement with the body ring 12, parallel side members 16—16 bent 40 inwardly slightly at 17—17 to form the

narrower portion which engages with the catch 14 and the flattened, tempered free end 13 which serves to provide a permanent resilience to the spring pin member.

The catch 14 may be made of any desired 45 material and is formed with a comparatively wide mouth with sloping sides 18—18 to permit of the easy admission of the narrow section 17—17 of the spring pin, a slight pressure on the said pin, being suffi- 50 cient to cause it to pass beyond the narrowest part of the entrance formed by the points 19—19.

As is obvious, when this device is to be 55 worn, the spring pin may be slipped under the hair and with the thumb and one finger of the same hand the barrette body and spring pin may be pressed together until the pin seats and locks itself in the catch. The barrette may be removed from the hair 60 of the wearer by the application of a prying pressure from one finger nail under the free end of the pin, which will effect its release from the catch.

I claim:—

65 A barrette comprising a body member, a catch thereon having a receptive opening consisting of angularly disposed side walls and a locking seat consisting of a rounded base and side walls disposed substantially 70 at right angles to the side walls of the receptive opening, and a resilient pin comprising an endless wire loop hingedly connected to the said body member and having substantially parallel side members, the free 75 end of the said loop being tempered whereby it may be forced inside of and released from the interior of the said catch on the body member.

WILLIAM T. BATTLE.
